Primary Examiner — Robin V Webster(74) *Attorney, Agent, or Firm* — DeLio, Peterson & Curcio, LLC; Robert Curcio**CLAIM**

The ornamental design for a filter cartridge with flange end, as shown and described.

DESCRIPTION

FIG. 1 is the front perspective view of the flange end of a filter cartridge according to the present invention;

FIG. 2 is the back perspective view of the flange end of a filter cartridge according to the present invention;

FIG. 3 is the left side view of the flange end of a filter cartridge according to the present invention;

FIG. 4 is the right side view of the flange end of a filter cartridge according to the present invention;

FIG. 5 is the top view of the flange end of a filter cartridge according to the present invention;

FIG. 6 is the front view of the flange end of a filter cartridge according to the present invention; and,

FIG. 7 is the back view of the flange end of a filter cartridge according to the present invention.

The broken line showing of portions of the filter cartridge is included for the purpose of illustrating and forms no part of the claimed design.

1 Claim, 3 Drawing Sheets(56)
